William Richards

UNITED STATES PATENT OFFICE.

MARCUS B. BAILEY, OF NEW YORK, N. Y., ASSIGNOR OF ONE-HALF TO HARRY MUNSON,
OF NEW YORK, N. Y.

REVERSIBLE MAT.

1,245,997.

Specification of Letters Patent.

Patented Nov. 6, 1917.

Application filed June 1, 1917. Serial No. 172,174.

To all whom it may concern:

Be it known that I, MARCUS B. BAILEY, a citizen of the United States, and a resident of New York, in the county and State of New York, have invented certain new and useful Improvements in Reversible Mats, of which the following is a specification.

This invention relates to improvements in foot mats, and particularly to types such as 10 are used in connection with the running board or steps of vehicles.

The principal object of the invention is to provide a mat which is readily reversible so that either side may be used.

15 A further object is to provide means combined with the mat whereby it may be firmly secured in operative position upon any extending flat surface.

A still further object is to provide a mat 20 which may be cheaply manufactured, and which possesses the elements of durability, strength and lightness to an extreme degree.

These and other like objects are attained by the novel construction and combination 25 of parts hereafter described and shown in the accompanying drawing, forming a material part of this disclosure, and in which:—

Figure 1 is a fragmental perspective view 30 showing the application of the mat to the running board of an automobile.

Fig. 2 is a fragmental top plan view of a mat made in accordance with the invention, the securing means being shown extended at 35 the ends.

Fig. 3 is an enlarged fragmental sectional view taken on line 3—3 of Fig. 2.

Fig. 4 is a transverse sectional view taken on line 4—4 of Fig. 2.

40 Fig. 5 is a side elevational view of the end element, and

Fig. 6 is a fragmental plan view taken at the end of the mat, and indicating the means for securing the attaching element.

45 In constructing a mat in accordance with the invention, a pair of round wire rods 15 are formed with eyes 16 at their ends, the rods being of the length it is desired to make the mat, and engaged in these eyes are trans-

50 verse rods 18, one of their ends being upset forming heads 19, while the opposite ends are bent, forming right angle elements 20, the length of which is slightly in excess of the thickness of the plate or board upon 55 which the mat is to be secured.

Continuing hook-like arms 21, formed with the elements 20, are bent obliquely toward the rods 18, reentrantly over the mat, and terminate in outwardly curved ends 22 adapted to engage and freely slide below 60 the surface of the plate to which the mat is engaged by the inherent resiliency of the material of the arms.

It is to be noticed that the heads 19 and angular bends 20 prevent longitudinal movement of the rods 18, but permit the same to be freely rotated therewith, so that the same may be folded closely adjacent to the side of the mat, or extended from either of its sides when in use.

Engaged with the frame side rods 15, are a plurality of relatively thin metallic plates or strips 24, their ends being coiled so as to tightly envelop the rods 15, the arrangement being such as to present spaces 25 between 75 adjacent strips and between the end strips and the frame end rods 18, the encircling bands 26 being affixed to the rods in such manner as to prevent motion of the strips upon them.

Interwoven between these strips and over the end rods 18 are cords 28, the same being of any preferred material, as cocoa fiber, hemp, or the like, the cords being tightly interlaced and pressed closely together side- 85 wise with sufficient tension to normally hold the rods 18 and hook arms 21 in any adjusted position.

From the foregoing, it will be evident that the thickness of the mat will be only twice 90 the diameter of the cord used, plus the thickness of the strips 24 upon which they are interlaced; also the peculiar engagement of each succeeding strand of the cord renders the mat exceedingly strong and very durable.

All the metallic parts are inclosed by the cord fiber, to such an extent that no part makes contact with the plate upon which the mat may be attached, thus avoiding scratching or otherwise damaging the finished surfaces of the plate or board, and it will be also seen that the hook elements 21 are readily reversible so that the mat can be used either side up with equal facility, and held firmly with relation to the plate upon which it is applied.

When not in use, the mats may be carried below the seat cushion or other narrow space, the hook elements 21 folding at such 110

time closely against the side surfaces of the mat, which is also their position when being transported in bulk quantities.

The operation and construction is thought to be clearly apparent, as is also its application, which merely consists of placing the mat upon the plate or running board, which is presumed to be of a thickness slightly greater than the distance between the curved ends of the hooks 21, and the rods 18, whereby the engagement of the hooks is sufficient to hold the mat very firmly in position, it merely being necessary to slide the same until the angular elements 20 contact with the outer edge of the board.

Having thus described my invention, what I claim as new, and desire to secure by Letters Patent, is:—

1. In a mat, the combination with a reversible body, of resilient hooks pivotally engaged in the extreme ends of said body, said hooks extending over said body and being operatively disposable on either side thereof.
2. In a mat, the combination with a pair of rods disposed in parallel and eyes formed in the ends thereof, of a pair of cross-rods disposed in the mentioned eyes, resilient hooks formed integrally with said cross-rods, means for preventing the longitudinal

movement of said cross-rods, and a mat interwoven between said rods.

3. In a mat, the combination with a pair of oppositely disposed parallel rods, eyes formed in the ends of said rods, flat metallic strips having ends encircling said rods, a fibrous cord interwoven alternately over and under said strips, end rods pivotally engaged in said eyes, and resilient hooks formed with said end rods, said hooks being adapted for engagement with a plate on either side of the mat.

4. In a mat, the combination with a pair of rods disposed in parallel, looped eyes formed in the extremities of said rods, a plurality of metallic strips, the ends of said strips encircling said rods, cords interwoven and intertwined between each succeeding strip, end rods rotatably engaged in said eyes, the bight of said cords passing over said end rods, angular elements formed with said end rods, and angularly disposed hooks formed with said angular elements, said hooks being adapted to be disposed upon either side of the mat or folded closely adjacent thereto.

In testimony whereof I have signed my name to this specification.

MARCUS B. BAILEY.
